DESIGN FOR A COMBINED BASKET RACK AND LIGHTING FIXTURE OR SIMILAR AR- TICLE

John L. Mohun, Chicago, Ill., assignor to The Adlake Company, a corporation of Illinois

Application April 13, 1936, Serial No. 62,099

Term of patent 14 years

To all whom it may concern:

Be it known that I, John L. Mohun, a citizen of the United States of America and a resident of Chicago, county of Cook, and State of Illinois, have invented a new, original, and ornamental Design for a Combined Basket Rack and Lighting Fixture or Similar Article, of which the following is a specification, reference being had to the accompanying drawing, forming a part thereof, wherein rack and lighting fixture showing my new design; Fig. 2 is a side elevational view; and Fig. 3 is a bottom plan view of the lighting fixture portion thereof and a fragment of the basket rack.

Fig. 1 is a perspective view of a combined basket

I claim:

The ornamental design for a combined basket rack and lighting fixture, or similar article, substantially as shown.

JOHN L. MOHUN.
